United States Patent Office

Des. 195,395
Patented June 11, 1963

195,395

SLIP

Richard Sidney Strauss, 5639 Netherland Ave.,
Riverdale, N.Y.

Filed Dec. 28, 1960, Ser. No. 63,376

Term of patent 3½ years

(Cl. D3—26)

The figure on the drawing is a front view of a slip showing my new design.

The characteristic features of my design reside in the combination on the darkly colored slip disclosed, of the relatively wide embroidered lace panel effect extending from the neck to the hemline on the front, which panel effect apparently passes beneath and is concealed by the waist yoke, substantially as shown.

The back of the slip is plain and unornamented.

I claim:

The ornamental design for a slip, substantially as shown and described.
